UNITED STATES PATENT OFFICE.

BLOOMFIELD BROWER, OF NEW YORK, N. Y.

CARD-INDEX OR THE LIKE.

SPECIFICATION forming part of Letters Patent No. 769,855, dated September 13, 1904.

Application filed November 16, 1901. Serial No. 82,503. (No model.)

To all whom it may concern:

Be it known that I, BLOOMFIELD BROWER, a citizen of the United States, residing at New York, county of New York, and State of New York, have invented certain new and useful Improvements in Card-Indexes or the Like, fully described and represented in the following specification and the accompanying drawings, forming a part of the same.

10 This invention relates to improvements in card-indexes, the improvements of the present invention as a whole having for their object the provision of a card-index which is more compact and can be more conveniently manipulated than the card-indexes in existence prior to the present invention.

15 The invention also relates to improvements in different parts or members of the card-index—that is to say, in the guiding member which extends longitudinally of the card-receptacle and which engages and interlocks with the index-cards, in the follower which slides on and is guided by such guiding member and engages and supports the stack of cards 20 in vertical position, and in the index-cards and memorandum-cards.

25 As a full understanding of the several improvements of the present invention can best be had from a detailed description of an organization embodying the same, such description will now be given in connection with the accompanying drawings, in which—

30 Figure 1 is a longitudinal section of a card-index embodying the present invention. Fig. 35 2 is a cross-section of the same, taken on the line 2 2 of Fig. 1. Fig. 3 is a detail view in perspective of a follower of a different form from that shown in Fig. 1. Fig. 4 is a similar view of another form of follower. Fig. 5 40 is a perspective view of one of the index-cards which is provided with novel means for engaging the guiding member of the card-index, said guiding member being shown by dotted lines as in engagement with the index-card; and Fig. 45 6 is a similar view of another form of index-card.

Referring to Figs. 1, 2, and 3 of said drawings, *a* indicates a suitable receptacle; *b*, index-cards; *c*, memorandum-cards stacked between

the index-cards; *d*, a follower which, as shown 50 in Fig. 1, engages the stack of index and memorandum cards and supports the same in vertical position, and *e*, a guiding member upon which the index-cards *b* are strung and which interlocks with the follower *d*, so as to guide 55 it in its movements longitudinally of the box to and from the stack of cards and at the same time prevent vertical displacement thereof.

55 The receptacle *a* is of usual construction except that by reason of certain peculiarities 60 in the construction and arrangement of the index-cards *b*, follower *d*, and guiding member *e*, forming part of the present invention and to which reference will be hereinafter made, the height of the receptacle is reduced 65 to a substantial extent, which is of considerable importance, as these card-indexes are used in large numbers in offices and libraries, and it is therefore necessary to economize as much 70 as possible the space which they occupy.

75 The receptacle *a* is provided at what may be termed its "rear end" with a block *f*, secured to the box, and the front face of which, facing the stack of index and memorandum cards, is inclined, so that the index and memorandum cards may be spread apart by hand at their upper ends when it is desired to consult a memorandum or to insert or remove a memorandum-card.

80 The block *f* is secured to the receptacle *a* in such way as to provide a space between its under side and the bottom of the receptacle, and to the under side of the block *f* is secured one end of the guiding member *e*, the opposite end of said guiding member being 85 free, as shown in Fig. 1. The guiding member *e* is made of spring metal, the resiliency of which tends to force its free end toward the bottom of the receptacle, and is preferably in the form of a flat strip and located in 90 close proximity to the bottom of the receptacle. One result of this construction and arrangement of the guiding member is that it occupies but little space vertically of the receptacle, which reduces the height of the receptacle, and at the same time this guiding member provides a broad flat seat for the 95 memorandum-cards, which will support and

maintain said cards in true vertical position and in proper alinement with each other. The guiding member being resilient also and free at one end, the index-cards *b* and follower *d* 5 can be readily slipped on and off by simply raising the free end of the guiding member *e*, as illustrated by dotted lines in Fig. 1. By reason also of the resiliency of the guiding member *e* and its close proximity to the bottom 10 of the receptacle the index-cards *b* and follower *d*, particularly when constructed according to the present invention, as herein-after described, are held steadily in position in the receptacle.

15 The follower *d* is formed from a sheet-metal blank bent so as to provide a base *d'*, preferably flat, which when the follower is in position in the receptacle *a* rests upon the bottom thereof, as shown, and a triangular 20 body portion which engages the stack of index and memorandum cards *b* *c*. The triangular body portion of the follower *d* is provided just above the base of the follower with an opening *d''*, which is elongated or in the 25 form of a slot corresponding to the shape in cross-section of the guiding member *e* and through which said guiding member passes, as shown. The follower *d* is also provided with a lip *d'*, formed by striking up the 30 metal above the opening *d''*, which engages the upper surface of the guiding member, the follower, by reason of such engagement and the engagement of its base *d'* with the under side of the guiding member, being frictionally locked to the latter against displacement when it is in engagement with the stack 35 of index and memorandum cards.

Both faces of the follower *d* may be inclined, as shown in Fig. 1, or only one face 40 thereof may be inclined, and the face which is thus inclined may be that next the stack of index and memorandum cards, as shown in Fig. 3, or that which is away from such stack of cards, as shown in Fig. 4.

45 The index-card *b* is of novel construction, being provided at its base with a flap *b'*, which when the card is in the receptacle rests under and engages the under side of the guiding member *e*, as shown in Figs. 5 and 6, the 50 body portion of the card just above the flap being provided with a slot or elongated opening *b''*, corresponding to the shape in cross-section of the guiding member *e*, which passes through said opening. The flap *b'* rests upon 55 the bottom of the receptacle and by reason of its engagement with the under surface of the guiding member, which is in close proximity to the bottom of the receptacle, supports the body of the index-card steadily in proper 60 vertical position. The flap *b'* may be continuous, as shown in Fig. 6, but will preferably be slit in line with opening *b''*, so as to leave angular projecting portions *b'* for engaging the under side of the guiding member

e, as shown in Fig. 5. The advantage of this 65 construction is that an index-card so formed may be introduced between the index and memorandum cards already in the receptacle and engaged with the guiding member *e* without removing the index-cards already strung 70 upon the guiding member, whereas with an index-card of the form shown in Fig. 6 such removal is necessary.

By "receptacle" as used herein I mean not only such a box or receptacle as that shown, 75 but also any document-box in which a follower is used—such, for example, as those commonly used for filing away papers.

It will be observed that by reason of the engagement of the base *d'* and lip *d''* of the 80 follower with the under and upper sides of the guiding member *e* the follower cannot be pushed back by the pressure of the stack of cards, but under such pressure more firmly 85 engages the guiding member, whereas the follower can be readily moved back and forth by hand by seizing it at its lower end and moving it in the desired direction.

What I claim is—

1. The combination in a suitable receptacle, 90 of a resilient guiding member free at one end and extending longitudinally of the receptacle in close proximity to the bottom thereof, and a follower comprising a base, the under surface whereof rests upon the bottom of the receptacle and the upper surface whereof engages the under side of the guiding member, and a body portion extending upwardly from said base and provided with an opening 95 through which the guiding member passes, 100 substantially as described.

2. The combination in a suitable receptacle, 105 of a resilient guiding member free at one end and extending longitudinally of the receptacle in close proximity to the bottom thereof, and a follower comprising a base, the under surface whereof rests upon the bottom of the receptacle and the upper surface whereof engages the under side of the guiding member, 110 and a body portion extending upwardly from said base and provided with a transverse slot or elongated opening through which the guiding member passes, said guiding member conforming substantially to said slot or elongated opening, substantially as described. 115

3. The combination in a suitable receptacle, 120 of a resilient guiding member free at one end and consisting of a flat strip extending longitudinally of the receptacle in close proximity to the bottom thereof, and a follower comprising a base, the under surface whereof rests upon the bottom of the receptacle and the upper surface whereof engages the under side 125 of the guiding member, and a body portion extending upwardly from said base and provided with a transverse slot or elongated opening corresponding to the shape in cross-section of the guiding member and through which

said guiding member passes, substantially as described.

4. The combination in a suitable receptacle, of a resilient guiding member free at one end 5 and extending longitudinally of the receptacle in close proximity to the bottom thereof, and a follower comprising a base, the under surface whereof rests upon the bottom of the receptacle and the upper surface whereof engages the under side of the guiding member, and a body portion extending upwardly from said base and provided with an opening through which the guiding member passes and with means extending away from the base 10 and said opening for engaging the upper surface of the guiding member, substantially as described.

5. The combination in a suitable receptacle, of a suitable guiding member extending longitudinally of the receptacle, and a follower made from a single piece of sheet metal and comprising base *d*' and a body portion bent upwardly therefrom and then downwardly, one face of said body portion thus formed being inclined, substantially as described.

6. The combination in a suitable receptacle, of a suitable guiding member extending longitudinally of the receptacle, and a follower made from a single piece of sheet metal and comprising base *d*' and a body portion bent upwardly therefrom and then downwardly, the face of said body portion next the stack of cards being inclined, substantially as described.

35 7. The combination in a suitable receptacle, of a suitable guiding member extending longitudinally of the receptacle and a follower made from a single piece of sheet metal and comprising base *d*' and a body portion bent

upwardly therefrom and then downwardly, 40 both faces of said body portion being inclined, substantially as described.

8. An index-card provided with a flap at its base and above said flap with an opening for the passage of a guiding member, said flap being adapted to engage the under side of such guiding member and thereby hold the card in position, substantially as described.

9. An index-card provided with a flap at its base and above said flap with a slot for the 50 passage of a guiding member, said flap being adapted to engage the under side of said guiding member and thereby hold the card in position, substantially as described.

10. An index-card provided with a flap at its base and above said flap with an opening for the passage of a guiding member, said flap being slit in line with said opening and provided with portions extending toward each other to engage the under side of such guiding member and thereby hold the card in position, 60 substantially as described.

11. An index-card provided with a flap at its base and above said flap with a slot for the passage of a guiding member, said flap being 65 slit in line with said slot and provided with portions extending toward each other to engage the under side of such guiding member and thereby hold the card in position, substantially as described.

70 In testimony whereof I have hereunto set my hand in the presence of two subscribing witnesses.

BLOOMFIELD BROWER.
